UNITED STATES PATENT OFFICE.

FRANCIS G. MATSON, OF WASHINGTON, DISTRICT OF COLUMBIA.

DESIGN FOR AN EDIBLE FOOD PRODUCT.

Application filed February 23, 1924. Serial No. 8,706. Term of patent 3½ years.

To all whom it may concern:

Be it known that I, FRANCIS G. MATSON, a citizen of the United States, residing at Washington, in the District of Columbia, have invented a new, original, and ornamental Design for an Edible Food Product, of which the following is a specification, reference being had to the accompanying drawings forming a part thereof.

Figure 1 is a perspective view of an edible food product embodying my new design,

Figure 2 is a plan view of the same,
Figure 3 is a bottom plan view of the same,

Figure 4 is an end elevation of the same,
and

Figure 5 is a side elevation of the same.

I claim:

The ornamental design for an edible food product, as shown.

FRANCIS G. MATSON.
